UNITED STATES PATENT OFFICE.

GODFREY H. LASAR, OF ST. LOUIS, MISSOURI.

TYPE-WRITING MACHINE.

SPECIFICATION forming part of Letters Patent No. 415,524, dated November 19, 1889.

Application filed October 11, 1886. Renewed July 19, 1889. Serial No. 318,042. (No model.)

To all whom it may concern:

Be it known that I, GODFREY H. LASAR, of the city of St. Louis, in the State of Missouri, have invented a certain new and useful Improvement in Type-Writing Machines, of which the following is a full, clear, and exact description, reference being had to the accompanying drawings, forming part of this specification, and in which—

10 Figure 1 is a rear elevation of the carriage and a transverse section through the key-levers of my improved machine. Fig. 2 is a top view of the carriage in the position shown in Fig. 1. Fig. 2^a is a detail view showing a 15 vertical transverse section on the line 2^a 2^a, Fig. 2. Fig. 3 is a front elevation of the carriage. Fig. 3^a is a top view of the track or carriage-supporting frame. Fig. 4 is a vertical transverse section of the carriage and escapement on line 4 4, Fig. 6, enlarged, looking in the direction of the arrows. Fig. 5 is a detail top view of the escapement enlarged. Fig. 6 is an enlarged rear view of the escapement. Fig. 7 is an enlarged perspective view of the 25 dogs of the escapement. Fig. 8 is a top view of same. Fig. 9 is a section thereof on line 9 9, Fig. 8, looking in the direction of the arrows. Figs. 10 and 11 are enlarged end views of the carriage, Fig. 10 showing the paper 30 shield or guard in normal position for printing and Fig. 11 showing it raised. Fig. 12 is an enlarged perspective view of one end of the carriage-rail. Fig. 13 is an enlarged perspective view of one of the sockets of the 35 track or carriage-supporting frame.

This invention relates to certain improvements in type-writers; and it consists in features of novelty hereinafter fully described, and pointed out in the claims.

40 Referring to the drawings, A represents the main frame, B the key-levers, and C the carriage, of the machine. The frame A is formed to receive the key-levers beneath it, as shown in Fig. 1, and beneath all the key-levers extends a rod or bar E, to which is connected an upwardly-extending bar or rod F, secured at its upper end to the dog G of the escapement, the dog having a lug G', perforated to receive a bolt G², that connects it to the upper end of the rod or bar F. (See Figs. 4, 7, and 9.) The perforation in the lug G' is

made in the form of a slot, so that the bolt G² may be shifted back and forth therein to regulate the vertical movement of the dogs. The rod or bar F is made in two parts, the 55 adjacent ends of the two parts being slotted to receive a connecting-screw F³. This allows of a lengthening or shortening of the rod or bar to regulate the movement of the dogs. The dog G is pivoted to move vertically, and 60 it is pivoted at G³ to a fixed arm H' of a pendent plate H. So it will be seen that each time a key-lever B is operated or depressed the dog G will be pulled down into the position shown in Fig. 9, and each time it is thus 65 pulled down it is brought into engagement with a tooth of the rack C' of the carriage.

Pivoted to the dog G at I' is another dog I, which is arranged to move horizontally on its pivot, and, as it is secured to the dog G, 70 it of course moves vertically therewith. When the dog G is in its upper position, the dog I engages the rack, and when the dogs are pulled down, as stated, the dog I is disengaged from the rack and is moved into the 75 position shown in Figs. 7 and 8 by a spring I², so that when the dogs move up again the dog I will engage the next notch to the one last occupied by it and the carriage will be allowed to move forward the distance of one 80 notch under the influence of the spring J. The spring J is stronger than the spring I², so that when the dogs rise the dog I is moved into line with the dog G by the movement of the carriage. The spring I² is made so that 85 it will throw the dog I into the position shown in Fig. 7 and no farther, as described, and at the same time it allows or permits the dog to be thrown around or out still farther when the carriage is run back to commence a 90 new line. The dogs and spring J are secured to the plate H, dovetailed into projection A' of the frame A, so that it can, when desired, be adjusted up or down by a set-screw M, the screw being held and working in lugs L' M', 95 secured to or formed upon the plate H and projection A', respectively. This construction I have described and shown in another application, Serial No. 215,904, filed October 11, 1886. The stem or arbor J', upon which 100 the housing of the spring J turns, is held from turning backward by a ratchet-wheel J² and

a pawl J^3 . (See Fig. 6.) By turning the wheel J^2 the spring J may be tightened. The track or carriage-supporting frame T , to which the plate-pendant H is secured, or upon which it is formed, and by which it is supported on the main frame, and upon which the carriage moves or travels, is made of longitudinal front rail F' , longitudinal central bar F^x , and horizontal end bars or pieces T^2 , (see Fig. 3^a), the end pieces projecting beyond the rear side of the central bar and having vertical extensions T^3 formed upon or secured thereto at their rear ends, the extensions having sockets T^4 on their upper ends to receive the rear rail of bar C^5 of the carriage, which moves back and forth therein as the machine is operated. The rail or bar C^5 has end flanges C^{20} and adjustable collars C^6 , provided with set-screws C^7 , the object of the collars being to regulate the movement of the carriage by adjusting them in or out, so that they will come against the extensions sooner or later, as desired. The object of the flanges is to limit the movement of the collars. The carriage has a front rail C^8 , (in addition to the rear rail C^5), and secured to this rail C^8 is a downwardly-extending arm C^9 , (see Figs. 3 and 4), having an inturned end C^{10} , that engages beneath the outer longitudinal piece T' of the track-frame, and above and bearing upon the piece is a roller C^{11} , journaled in arm C^9 , to reduce the friction between the arm and piece. This guides and supports the front part of the carriage. The carriage is provided with an adjustable paper-guard N , made in two pieces N' N^2 , the piece N^2 being hinged or pivoted to the rail C^8 of the carriage. The horizontal part N' of the guard has an upturned inner edge N^3 , which directs the paper upward under the vertical part N^2 of the guard. The direction in which the paper is inserted is shown by dotted lines, Fig. 4, it passing above the part N' of the guard. The upper edge of the part N^2 has a comb N^4 hinged to it by a rod N^{30} and strips N^{31} , as shown, the action of which is to keep the paper down upon the roller. The comb may be turned from the operator or from the position shown in Figs. 2 and 4 out of the way of the type toward the rear of the machine into the position shown in Figs. 10 and 11, after the paper is inserted, to permit the type to strike between the part N^2 and the rod of the comb. The part N^2 is adjusted to and from the roller of the carriage by turning it on the rail C^8 , for which it is provided with a lever C^{16} , having a dog C^{17} , engaging ratchet-teeth C^{18} on one of the ends C^{12} of the carriage. The dog is held into engagement with the ratchet-teeth by a spring C^{19} , secured in an opening or socket C^{20a} of the lever. The dog has an arm C^{21} , against which the spring bears, (see Fig. 4), and this arm extends beyond the lever, so that by pressing thereon the dog may be disengaged from the ratchet-teeth to move the

part N^2 of the guard back from the roller of the carriage.

I claim as my invention—

1. In a type-writer, in combination with the carriage and keys, the track-frame, adjustable plate to which the track-frame is secured, horizontally-pivoted dog secured to said adjustable plate, spring-dog pivoted to the horizontally-pivoted dog, adjustable rod connected to last-mentioned dog, and rod or plate extending beneath the keys of the machine and to which the adjustable rod is connected, substantially as and for the purpose set forth. 80

2. The combination of the main frame having an upward projection, the track or carriage-supporting frame consisting of a longitudinal central bar having a pendent plate at the middle portion by which it is supported on the upward projection, an arm projecting rearwardly from the top of the plate, the longitudinal front rail, the transverse end bars projecting beyond the rear side of the central bar, and the vertical extensions on the rear ends of the end bars having sockets at their upper ends, an escapement on the arm, and a carriage having a front rail provided with a roller bearing on the front rail of the track or carriage-supporting frame and a rear rail sliding in the sockets. 90

3. The combination of the track or carriage-supporting frame consisting of a longitudinal central bar having a pendent plate at the middle portion, by which it is supported on the main frame, the longitudinal front rail, the transverse end bars projecting beyond the rear side of the central bar, and the vertical extensions on the rear ends of the end bars having sockets at their upper ends, a carriage, 100 a front rail on the carriage having a pendent arm formed with inturned lower end engaging beneath the front rail of the frame, a roller journaled to the said pendent arm and bearing on the front rail of the frame, and a rear rail on the carriage sliding in the sockets. 110

4. In a type-writer, in combination with the carriage having a roller, the two-part guard N , the horizontal part N' having a curved extension N^3 and the vertical part N^2 adjustable to and from the roller, substantially as and for the purpose set forth. 115

5. In a type-writer, in combination with the carriage having a roller, the two-part guard, the inclined part having a comb, substantially as and for the purpose set forth. 120

6. The combination, with a carriage having a roller-platen, of the guard comprising the horizontal part N' , having upturned inner edge N^3 , the vertical part N^2 , hinged to the front rail of the carriage, and a lever and pawl-and-ratchet mechanism by which the vertical part is adjusted to and from the roller independent of the horizontal part. 125

7. In a type-writer, in combination with the carriage having a roller, the guard hinged to the front rail of the carriage, lever secured to

the guard at the rail, spring-dog secured to the lever and engaging teeth on the end of the carriage, and arm on the dog extending beyond the lever, substantially as set forth.

5 8. In a type-writer, in combination with a track-frame T, formed with longitudinal pieces and horizontal end pieces T³, having vertical extensions T³, provided with sockets on their upper ends, the carriage having a rail C⁵, provided with flanges C²⁰, and the adjustable collars C⁶ on the rail, substantially as set forth.

9. In a type-writer, in combination with the key-levers and carriage provided with a rack, the track-frame, the fixed and pivoted dogs ¹⁵ for engaging the carriage-rack, lug G' on the fixed dog, having a slot, connecting-bar F, and connecting-bolt G², substantially as and for the purpose set forth.
